UNITED STATES PATENT OFFICE

131,053

DESIGN FOR A MITTEN

Richard G. Stall, Brockton, Mass., assignor to
Stall & Dean Manufacturing Company, Brock-
ton, Mass., a corporation of Massachusetts

Application September 9, 1941, Serial No. 103,259

Term of patent 3½ years

To all whom it may concern:

Be it known that I, Richard G. Stall, a citizen
of the United States, residing at Brockton, coun-
ty of Plymouth, and State of Massachusetts,
have invented a new, original, and ornamental
Design for a Mitten, of which the following is
a specification, reference being had to the ac-
companying drawing, forming a part thereof.

Fig. 1 is a rear view of a mitten, showing my
new design; and

Fig. 2 is a side view of the mitten shown in
Fig. 1.

The front or palm portion of the mitten of said
views illustrating the design is there conven-
tionally plain.

I claim:

The ornamental design for a mitten, substan-
tially as shown and described.

RICHARD G. STALL.
